(57) **CLAIM**

The ornamental design for a bracket, as shown and described.

DESCRIPTION

FIG. 1 is a front view of the bracket;

FIG. 2 is a back view thereof;

FIG. 3 is a bottom view thereof;

FIG. 4 is a top view thereof;

FIG. 5 is a left-side view thereof; and,

FIG. 6 is a right-side view thereof.

The broken lines shown in the figures are for illustrative purposes only and form no part of the claimed design.

The claimed design is shown broken away to indicate indeterminate length.
